Patented Nov. 28, 1922.

INVENTOR.
RALPH MAZE.
BY Drury, Strong, Townsend
and Loftus ATTORNEY.S.

UNITED STATES PATENT OFFICE.

RALPH MAZE, OF HOLLISTER, CALIFORNIA.

BUILDING CONSTRUCTION.

Application filed February 13, 1922. Serial No. 535,986.

To all whom it may concern:

Be it known that I, RALPH MAZE, a citizen of the United States, residing at Hollister, county of San Benito, and State of California, have invented new and useful Improvements in Building Constructions, of which the following is a specification.

This invention relates to building construction, and particularly pertains to means for veneering a building wall with fire-proof material.

Heretofore building walls have been veneered by the use of brick or tile members and in some instances by applying a coating of plaster or stucco. The former structures have been expensive and the plaster work has been objectionable due to the fact that the action of the elements often expand the wall beneath and cause the plaster to break away. It is the principal object of the present invention to provide a veneer for building walls which embodies a sealing layer of cementitious material over which a suitable slightly veneer of precast, fire-proof material is secured, said precast members acting as an outer form for the cement.

The invention is illustrated by way of example in the accompanying drawings in which:

30 Fig. 1 is a view in perspective showing a fragmentary portion of a building wall to which the present invention has been applied.

Fig. 2 is a view in perspective showing one of the veneering blocks.

Fig. 3 is a view in vertical section and elevation showing the composite structure of the wall when it is completed.

Fig. 4 is an enlarged view in perspective showing one of the corner veneering elements.

Referring more particularly to the drawing, 10 indicates a wall which is to be veneered. This wall is usually formed by sheeting 11 secured to a suitable frame structure. The outer face of the sheeting is preferably covered with building paper as indicated at 12. In the present instance fastening staples 13 are driven through the building paper and into the sheeting. These staples are U-shaped and have a flat portion

which is intended to lie parallel to the flat surface of the wall. For the sake of convenience it might be found desirable to prepare the building paper by printing spots 55 13' on it to indicate the approximate positions to be assumed by the staples.

The staples are intended to receive hook elements 14 of veneer blocks 15. These hooks have one end cast in the block and 60 extending rearwardly and downwardly from the back face of the block. It may be desirable to provide two or more of these hooks and in some instances spacing members 15 may be incorporated in the blocks 65 to extend from the rear face thereof. These spacing members are disposed at opposite ends of the back of the block and it is intended that their flat portions shall rest firmly against the wall to hold the blocks 70 from rocking or other displacing movement, as more clearly shown in Fig. 3.

In forming corners it is desirable to provide corner members 16. These are quarter round in section and have recessed portions 75 17 at their opposite ends. Pins 18 extend longitudinally of these recesses and project through staples 19 which are secured directly in the projecting corners of the wall.

It will be understood that the veneering 80 blocks may be of any dimensions and due to the fact that they are preferably formed of plastic material, may be of any design. It is highly desirable, however, to form marginal recesses 19 along the edges of the rear 85 face of each block. These recesses of adjacent blocks will combine to form a key portion 20, as indicated at Fig. 3, thus tending to more firmly hold the blocks in position and to more thoroughly seal the joints between them.

In operation of the present invention a wall may be prepared for veneering by first applying the building paper 12. After this has been done the fastening staples 13 may 95 be driven into the wall at suitable stations to properly receive the fastening hooks 14. Attention is directed to the fact that the staples are of considerable width, thus making it unnecessary to accurately place them 100 and insuring that without great difficulty the blocks may be set in their proper posi-

tions. When the staples 13 have been engaged by the hook portions 14 the outwardly extending lengths 14' of the hooks will rest upon the staples, while the projecting ends 5 of the hooks will lie flat against the wall. This may be found sufficient to properly hold the blocks in position. In some instances, however, it may be deemed desirable to fit the blocks with the spacing members 10 15'. These members will rest against the wall at opposite ends of the blocks and will prevent any rocking movement of the blocks and will insure that a predetermined space will be formed between the backs of the 15 blocks and the wall. When the veneered portion of the wall has been assembled this may be used as a form into which cementitious material 21 may be poured. This material will pass down between the backs of 20 the blocks and the partition and when set will hold the blocks in their locked positions and in rigid relation to each other.

It will thus be seen that by the present invention a solid wall of cementitious material 25 may be applied to the outer face of a timber wall and at the same time a neat and attractive outer veneer may be applied to the solid layer of cement, thus forming a complete fire-proof armor for the outer face of the 30 wall and at the same time permitting the wall to have a permanent and slight appearance.

While I have shown the preferred form of my invention as now known to me, it will 35 be understood that various changes might be made in the combination, construction and arrangement of parts by those skilled in the art, without departing from the spirit of the invention, as claimed.

40 Having thus described my invention, what I claim and desire to secure by Letters Patent is:

1. In a building construction, a veneering slab formed of plastic material, said slab 45 having securing means extending from its back to engage complementary fastening members applied to a wall, and means for holding the slabs in spaced relation to said wall, the rear of said slabs being formed 50 with a marginal recess to provide a key for cementitious material adapted to be applied to the joints between the assembled blocks.

2. In combination with a wall structure, a 55 plurality of pre-formed veneering slabs having rearwardly extending hooks embedded therein, projections secured to the wall engageable with said hooks whereby the slabs are held in spaced relation to the wall and intimate contact with each other, and a layer 60 of cementitious material poured between the main wall and the veneered wall formed by the slabs, whereby said material will combine with the slabs to form a solid fire-proof outer wall.

65 3. In combination with a wall structure, a

plurality of pre-formed veneering slabs, a plurality of hook-like projections secured in each slab and projecting equi-distant from the rear face thereof, a plurality of inter-spaced projections secured to outer face of 70 the wall and engageable with the projections on the slabs, such engagement supporting the slabs in spaced relation to the wall and in close proximity to each other and a layer of cementitious material poured between the 75 main wall and the assembled slabs, said slabs having recesses formed on their inner face whereby they will be keyed to the cementitious material.

4. In a building construction, a plurality 80 of hooklike projections applied to the outer face of a wall to be veneered, said projections placed in pre-determined positions, a plurality of slabs having rearwardly extending hook-like projections engageable 85 with the first named projections, such engagement when the said slabs are assembled causing them to be correctly spaced in relation to the wall and in close proximity to each other, said slabs having a marginal recess formed about their inner face, and a layer of cementitious material poured between the assembled slabs and the wall whereby said material will combine with the 90 slabs and enter said recesses to key said slabs 95 to the material to form an outer fire-proof wall.

5. In a building construction, a wall to be veneered, a moisture proof covering applied to the outer surface of said wall, a plurality 100 of U-shaped fastening elements driven into said wall at pre-determined points, a plurality of pre-formed veneering slabs each having a plurality of hook like projections protruding from their inner face a predetermined distance, said projections being adapted to engage the said U-shaped elements on the wall when the slabs are being assembled and thereby support the slabs a predetermined distance from the wall and in proper relation to each other, said slabs being formed with an inner marginal recess, and a layer of cementitious material in said recess, and a layer of cementitious material 110 poured between the assembled slabs and the 115 wall, said material entering the recesses and otherwise combining with the slabs to form an outer fire-proof wall.

6. In combination with a wall veneered by pre-formed slabs, of a corner member 120 adapted to be positioned between the ends of the veneering of right angularly extending walls during the veneering thereof, projecting U-shaped members driven in the wall being veneered, pins embedded in the corner 125 member and having portions engageable with said projecting members, to support the corner member relatively to the veneering and the wall, said member being united with the veneering by cementitious material. 130

7. In combination with a wall structure, a plurality of pre-formed contiguous veneer slabs having flat inner faces and provided with marginal recesses extending along the adjacent edges of the slabs at the said inner face of the same, complementary fastening elements on the wall and the slabs en-
- gaging each other and supporting the slabs and spacing the same from the wall, and a layer of cementitious material poured between the slabs and the wall, said material entering the recesses to key the slabs. 10

RALPH MAZE.
